GEORGE W. BAUGHMAN, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING SYSTEM

Application filed December 5, 1930. Serial No. 500,314.

My invention relates to railway traffic controlling systems of the coded track circuit type. One feature of my invention is the provision of novel and improved coding and decoding apparatus for use in systems of this type.

I will describe certain forms of apparatus embodying my invention, and will then point out the novel features thereof in claims.

10 In the accompanying drawings, Fig. 1 is a diagrammatic view of one form of decoding apparatus embodying my invention. Fig. 2 is a diagrammatic view showing one form of coding apparatus embodying my invention. Fig. 3 is a diagrammatic view of a modified form of decoding apparatus also embodying my invention. In the drawings, similar reference characters refer to similar parts in all views.

20 In accordance with my present invention, an alternating current of a given frequency is periodically interrupted or coded into impulses of equal duration. These impulses are arranged into groups each having a given 25 number of impulses. The groups are separated by an impulse or "on period" of the alternating current that is of much longer duration than the duration of a single impulse of the group. Each particular code 30 is therefore distinguished by the number of short impulses between two long impulses. Assuming that an alternating current of 100 cycles is periodically interrupted or coded 35 180 times per minute—that is, three cycles per second, then each cycle consists of an "on" period during which current flows, and the "off" period during which no current flows, which is $\frac{1}{3}$ second in duration. I 40 shall assume throughout this description that the long impulse that separates a group of such short impulses is of 0.5 second duration. One code of my invention will have a group 45 that consists of two full cycles of the 180 code impulses followed by an impulse of the 0.5 second duration and this arrangement will then be consecutively repeated. Such a code I prefer to employ for establishing a distinctive indication. A second code may consist of a group of three full cycles of the 50 short impulses followed by a long impulse

and this group when consecutively repeated will establish a second and different indication. A third code may consist of a group of four complete cycles of the short impulses followed by a long impulse and this group when consecutively repeated establishes a still different indication. Likewise other groups of impulses can be provided to establish other indications. In one form of my invention here disclosed I propose to employ a code of two full cycles of the short impulses followed by the long impulse to establish a caution or approach signal indication; a code of three full cycles of the short impulses followed by the long impulse to establish an approach restricted signal indication; and a code of four cycles of a short impulse followed by a long impulse to establish a proceed signal indication.

It is apparent that in such an arrangement, a large number of different indications can readily be established. Furthermore by utilizing a second and different frequency other than the 180 assumed, say a frequency of 120 cycles per minute, then still other 55 indications can readily be established without greatly increasing the apparatus required.

While in this description a code frequency of 180 cycles per minute is assumed and the long impulse taken as being of 0.5 second duration and these impulses grouped as mentioned above to produce certain indications, it will be understood that some other grouping of the impulses can be used and that the duration of a long impulse can be something other than 0.5 second without departing from the spirit and scope of my invention.

As a matter of fact in the second form of the apparatus here disclosed in the Fig. 3, the short impulses when not arranged in groups are utilized to establish the approach indication, while a group of two full cycles of short impulses separated by a long impulse establishes an approach restricted indication, and a group of three cycles of short impulses followed by a long impulse establishes a proceed indication. Where train carried apparatus is set to establish a proceed indication only after a certain definite number of short impulses of a given frequency

is followed by a long impulse of a predetermined duration, a false indication, due to shock excitation when operating on an electric road or when the train is operating over 5 non-coded alternating current track circuits, is a very remote possibility.

Referring to Fig. 1, the decoding apparatus, which as here shown is located on a train, includes two magnetizable cores 12 and 10 13 located in advance of the first pair of wheels, as is the practice in train control systems of this character. The cores 12 and 13 are disposed in inductive relation with the two track rails X and Y. The core 12 is provided with the winding 14 and the core 13 is provided with a similar winding 15 and the two windings 14 and 15 are connected in series so that voltages induced therein by an alternating current flowing in opposite directions in the two track rails at any given instant are additive. These two windings are connected preferably through an amplifying device indicated by the reference character 16 with a controlling relay designated 15 20 by the reference character MR and which relay I shall speak of as the master relay.

This master relay MR is preferably of the direct current polarized type, commonly employed in code systems of train control, having 30 a polarized armature 9 that remains in the position to which it was last moved until the relay is energized with reverse polarity. As is the usual practice in code systems, the electromagnet of the master relay MR is 35 controlled by the amplifying device in a manner such that the building up of energy induced in the cores 12-13 creates an impulse of current in the electromagnet of the relay MR which is of a polarity that will 40 position the polarized armature 9 in the right-hand position—that is, the position as shown in the Fig. 1. The dying away of the energy induced in the cores 12-13 creates a current impulse in the electromagnet of the relay 45 MR which is of a polarity that positions the polarized armature 9 in the left-hand position—that is, a position reversed to that shown in the Fig. 1.

It follows then that each time the cores 50 12-13 become energized as the result of an alternating current impulse flowing in the rails X and Y, an impulse of energy is supplied to the electromagnet of the relay MR, the polarity of which is such that the polarized armature 9 is positioned in the right-hand position. Each time the cores 12-13 55 become deenergized as the result of a period during which no current flows in the rails X and Y, an impulse is supplied to the electromagnet of the relay MR of a polarity which positions the polarized armature 9 in the left-hand position. In the event there is a prolonged period during which 60 current is steadily induced in the cores 12 and 13, the polarized armature 9 remains in the

right-hand position and in the event there is a prolonged period during which no current flows in the rails X and Y, the polarized armature 9 remains in the left-hand position. In other words, this master relay 10 MR is a polarized relay which is energized alternately in opposite directions in step with the energizing and deenergizing of the cores 12-13.

The relay MR controls two slow-releasing 15 relays 1A and 1 in such a manner that these relays are alternately energized when the master relay MR is energized alternately, in opposite directions. That is to say, when the armature 9 swings to the left-hand, the 20 relay 1A is energized by current from the positive terminal B of a train carried source that is not shown in the Fig. 1, through armature 9, wire 17, winding of relay 1A and to the negative terminal C of the source of 25 current. With armature 9 next swinging to the right-hand position, the relay 1 becomes energized by current from the positive terminal B through the armature 9 in the right-hand position, wire 18, armature 19 of the relay 1A now in its raised position, wire 20, winding of relay 1 and to the negative terminal C. With the armature 9 alternately swinging between its two positions, these 30 two slow-releasing relays 1A and 1 are retained energized as long as the cycle of operation of the armature 9 is less than the release period of the relays. With the armature 9 held in the right-hand position for a period greater than the release period of the 35 relay 1A, then its armatures 19 and 21 drop and if the armature 9 is held in the left-hand position for a period greater than the release period of relay 1, its armatures 85, 23 and 24 drop. Also, if the relay 1A remains 40 deenergized for a period greater than the release period of relay 1, the armatures of the 45 relay 1 drop.

The slow-releasing relays 1A and 1 with the master relay MR control a series or chain 50 of relays designated in the Fig. 1 by the reference character 2A, 2, 3A, 3, 4A, 4 and 5A. These relays are adapted to be arranged into groups. For illustration, the relays 1A, 1, 2A and 2 for a group that is used under certain conditions as will presently appear. The relays 1A, 1, 2A, 2, 3A and 3 form a second group that is used under certain other conditions. The relays 1A to 4 inclusive form a third group that is used under still other conditions, and the relays 1A to 5A inclusive 55 form a fourth group active at times. While the above group of relays are deemed sufficient to fully disclose my invention, additional relays to form additional groups 60 can be readily provided when the occasion demands.

On the first movement of the armature 9 to the left, the relay 1A picks up, and then as the armature 9 swings back to the right, 65

hand, the relay 1 picks up in the manner previously pointed out. On the second movement of the armature 9 to the left, the relay 2A picks up by current supplied from the positive terminal B through the armature 9, armature 23 of relay 1, back contact of the armature 25 of the relay 2, wire 26, winding of relay 2A and to the negative terminal C. During the interval the armature 9 occupies this left-hand position after relay 2A picks up, the relay 2 has both terminals of its winding connected to the positive terminal of the source of current, but as soon as the armature 9 swings to the right-hand position, the relay 2 picks up by current supplied from the positive terminal B, through armature 85 of the relay 1, wire 27, winding of relay 2, wire 28, armature 29, winding of relay 2A and to the negative terminal C. As long as the relay 1 is now retained energized, these two relays 2A and 2 are energized by the circuit that includes the coils of the relays in series. On the third movement of the armature 9 to the left, the relay 3A is picked up by the circuit from the positive terminal B, armature 9, armature 23, armature 25, back contact of the armature 30 of the relay 3, winding of the relay 3A and to the common terminal C. As the armature 9 next swings to the right, the relay 3 is picked up by the circuit through armature 32 in a manner similar to that just described for the relay 2. From this point on the relays 3A and 3 are retained energized as long as the relay 1 remains energized. On the fourth movement of the armature 9 to the left, the relay 4A is picked up by the circuit from the positive terminal B through the armature 9 and the armatures 23, 25 and 30 and the back contact of the armature 86 of the relay 4. Then on the next swing of the armature 9 to the right, the relay 4 is picked up by the circuit through armature 35 in a manner similar to that pointed out for the relay 2 and from this point on, the relays 4A and 4 remain energized as long as the relay 1 is energized. On the fifth movement of the armature 9 to the left, the relay 5A is picked up by a circuit that includes armatures 23, 25, 30 and 86 as will be readily understood by an inspection of the Fig. 1 and once relay 5A is up, it is retained energized by a circuit supplied with current from the positive terminal B through the armature 85 of the relay 1 and the front contact of its own armature 36. It follows that from this point on, the operation of the armature 9 of the master relay MR to periodically energize the relays 1A and 1 results in the group of relays 2A—2, 3A—3, 4A—4, and 5A being retained energized. That is to say that as long as armature 9 continues to swing between its two positions in step with the 180 code impulses that are alternately energizing and deenergizing the cores 12 and 13, the chain

of relays shown in Fig. 1 is energized. These relays control traffic governing relays designated by the reference characters L, R and A. With the relays 1A to 5A inclusive energized in the manner above described, it is apparent from an inspection of the Fig. 1, that the relays L, R and A are each on open circuit, their control circuits being open at the back contact of the armature 21 of the relay 1A. Also, the circuit is open at the back contact of the armature 37 of the relay 5A for the relay A, and at the back contact of the armature 38 of the relay 4 for the relay R, and at the back contact of the armature 39 of the relay 3 for the relay L. Under this de-energized condition of the relays L, R and A, a circuit is closed to the cab indicator light 40 from the positive terminal B through the back contacts of the armatures 41, 42 and 43 respectively. In the event the chain of relays 1A to 5A inclusive are all deenergized due to non-operation of the master relay MR, it is apparent that the traffic governing relays L, R and A are likewise all deenergized, their control circuit being open this time at the armature 24 of relay 1 and armature 87 of relay 2. Thus in Fig. 1 a continuous repeating of the 180 code impulses, or a failure of power, produce the same cab indication, namely that displayed by the cab signal 40.

Let us now consider the case where at the end of four complete cycles of short impulses, there follows an "on" period that is made long by the addition of a 0.5 second impulse—that is, this impulse is approximately 0.5 second plus the normal "on" period. Starting from the dying away of a long impulse the first code cycle results in a movement of the armature 9 to the left and then back to the right, during which time the relays 1A and 1 pick up in the manner previously described. During the second complete code cycle, the armature 9 makes its second movement to the left and back to the right and this second movement results in relays 2A and 2 being picked up in the manner above described. During the third cycle, the armature 9 makes its third movement to the left and back to the right and the relays 3A and 3 are picked up. Likewise during the fourth code, the armature 9 makes its fourth movement and the relays 4A and 4 are picked up. The next code "on" period being prolonged by the addition of a long impulse, the armature 9 remains in the right-hand position throughout the interval of this long impulse. The relay 1A being left without energy during this long impulse, its armatures 19 and 21 drop due to its slow-release period being less than the interval of the long impulse. The dropping of the armature 19 opens the circuit to relay 1 and at the expiration of its release period, which is also less than the long impulse, its armatures 85, 23 and 24 drop. The dropping of the armature 85 cuts off en-

ergy from each of the group of relays, namely 2A—2, 3A—3, and 4A—4 and these relays then become deenergized. At the dying away of the long impulse, armature 9 swings to the left and the relay 1A is again energized and during the next four cycles of the short impulses, the chain of relays 1 to 4 inclusive are again energized which is then followed by the relays all being again deenergized at the next long impulse. This action of energizing this group of relays and then deenergizing them is consecutively repeated as long as this code of four short impulses followed by a long impulse remains in effect. The result of this action is that a circuit to the traffic governing relay A is closed during the time relay 1A is down and the remaining relays are up. Looking at Fig. 1, as soon as the relay 1A drops, and before the remaining relays 1 to 4A, inclusive, are deenergized, a circuit is closed from positive terminal B through the back contact of the armature 21 of relay 1A, front contact of the armature 24 of the relay 1, front contact of the armature 87 of the relay 2, front contact of the armature 39 of the relay 3, front contact of the armature 38 of the relay 4, back contact of the armature 37 of the relay 5A, coil of the relay A and to common terminal C. With the relay A energized, then a circuit is established to the cab indicator 45 through the front contact of the armature 41 of the relay A. The relay A is slow-releasing and its release period is made greater than the total time consumed by the group of four short impulses plus the long impulse. It follows then that relay A remains up and the cab indicator 45 continuously displayed as long as the code consisting of groups of four short impulses separated by a long impulse remains in effect.

In the event the code consists of a group of but three complete cycles of the short impulses between successive long impulses, it is apparent that the relays 1A and 1 will be picked up on the first cycle, the relays 2A and 2 picked up on the second cycle and relays 3A and 3 on the third cycle, and then this group of relays deenergized during the long impulse. Under this condition, the traffic governing relay R is energized during the interval the relay 1A is down and the remaining relays 1, 2 and 3 are up, the circuit being from the positive terminal B through the back contact of the armature 21, armature 24 up, armature 87 up, armature 39 up and the armature 38 of the relay 4 down, coil of relay R and to common terminal C. The relay R is slow-releasing and its release period is greater than the combined time consumed by a group of three short impulses plus the long impulse. With the armature 42 of the traffic governing relay R up, then current is supplied to the cab indicator 46 by a circuit from the positive terminal B through

the back contact of the armature 41 of relay A and a front contact of the armature 42 of the relay R.

In the event that the code consists of a group of two short impulses between two successive long impulses, then the relays 1A and 1 are energized during the first cycle and the relays 2A and 2 energized during the second code cycle and then all deenergized during the long period. This operation results in the traffic governing relay L being energized during the interval that the relay 1A is down and the relays 1 and 2 are up, the circuit including the back contact of armature 21, front contact of armatures 24 and 87 and back contact of armature 39. Relay L is a slow-releasing relay having a release period greater than the time consumed by the group of two short impulses plus a long impulse. With the relay L energized so as to raise its armature 43, a circuit is completed to the cab indicator 47. To sum up the operation thus far, the train carried apparatus of Fig. 1 establishes a different cab signal for each of the different codes cited.

Referring to Fig. 2, the track rails X and Y are arranged in track sections only one of which is shown. Normally traffic through the section is in the direction indicated by the arrow. Each track section is provided with a track relay TR which is connected across the track rails X and Y at the entrance end of the section. Normally an alternating current of a convenient frequency such as 100 cycles per second is supplied to the track relay by a track transformer T located at the exit end of the section, the secondary 48 of the transformer T being connected across the track rails X and Y through the usual current limiting reactor 49. The primary 50 of the track transformer T is connected to the secondary 51 of a line transformer N whose primary 52 is supplied with energy from a generator G over the transmission line E. The connection from the secondary 51 of the line transformer N to the primary 50 of the track transformer T includes a front contact of the armature 53 of a code transmitting relay CT. Normally this relay CT is retained energized by current from the positive terminal B of a convenient source of current but which is not shown in Fig. 2, back contact of an armature 54 of an approach energizing relay AP to be shortly described, wire 55, winding of the relay CT, wire 56 and to the negative terminal C. The approach energizing relay AP is normally deenergized, its circuit being normally open at the back contact of armature 57 of the track relay TR. This circuit for the relay AP is further controlled in a manner to be shortly pointed out.

Each track section of my invention is provided with relays designated by the reference characters HR, DR and ADR. These relays

respond to traffic conditions in advance, according to the standard practice, and for the sake of clearness, the control circuits for these relays are not shown in Figure 2, as they form no part of my invention. It is deemed sufficient to say that the relay HR is deenergized whenever the first track section in advance is occupied,—that the relay DR is deenergized whenever either of the next two track sections in advance is occupied and that the relay ADR is deenergized when any one of the next three track sections in advance is occupied. It will be understood, however, that these relays HR, DR and ADR may be controlled by means of levers of an interlocking machine or they may be controlled from a dispatcher's office by a centralized traffic control system.

Each track section is provided with a plurality of relays that may be arranged into groups similar to those described in connection with the train carried apparatus of Fig. 1. These relays are designated in Fig. 2 by the reference characters 11A—11, 22A—22, 33A—33 and 44A—44. These relays are arranged in groups and connected by circuits identically the same as described for the several groups of relays of the Fig. 1, except there is no relay in Fig. 2 corresponding to the relay 5A in Fig. 1.

The approach energizing relay AP as stated above is normally deenergized and is supplied with energy whenever the track relay TR is shunted. The circuit for the relay AP is also controlled by the traffic controlling relays HR, DR, ADR and also by the groups of relays. One circuit for relay AP may be traced from the positive terminal B, through back contact of the armature 57, line wire 58, winding of the relay AP, front contact of armature 59 of the CT relay, wire 60, front contact of armature 61 of relay HR, front contact of armature 62 of relay DR, front contact of armature 63 of relay ADR, wire 64, back contact of the armature 65 of the relay 44 and to the negative terminal C. In the event that the relay HR is energized and relay DR deenergized, then the circuit for the relay AP is completed through a back contact of the armature 62, wire 66, back contact 67 of the relay 22, and to the common terminal C. Again in the event relays HR and DR are energized and relay ADR deenergized, then the circuit for the relay AP is completed through a back contact of the armature 63, wire 68, back contact of the armature 69 of the relay 33 and to common terminal C. It will be observed that when the relay AP becomes energized to pick up its armature 54, the circuit to the relay CT is open and that the relay CT becomes deenergized, and that the deenergizing of relay CT opens the circuit to the relay AP at the front contact of the armature 59. It follows that whenever the cir-

cuit for relay AP is complete there will be an alternate energizing and deenergizing of the relays AP and CT. Inasmuch as the energizing and deenergizing of the relay CT periodically interrupts the circuit to the primary 50 of the track transformer T, this above action of the relays AP and CT results in the coding of the alternating current supplied to the track rails X and Y. The natural period of operation of the relay CT and AP is so chosen that they will complete a cycle of being energized and deenergized at the rate of 180 times per minute.

Each release and picking up of the relay CT is counted on the chain of relays 11A to 44 inclusive in the following manner. The first deenergization of the relay CT energizes the relay 11A by current from the positive terminal B through the back contact of the armature 70, wire 71, winding of the relay 11A and to the negative terminal C. The relay 11A is made slow-releasing so that it will remain energized as long as the relay CT continues to be operated at the rate of 180 times per minute. On the next picking up of the relay CT, the relay 11 is energized through the front contact of armature 70 and the front contact of the armature 72 of the relay 11A. Relay 11 is made slow-releasing, and it will also remain energized as long as relay CT continues to operate at the rate of 180 times per minute.

On the second deenergization of the relay CT, the relay 22A is energized through the back contact of armature 70, the front contact of the armature 73 and a back contact of the armature 74 of the relay 22. On the next picking up of the relay CT, the relay 22 becomes energized by the circuit that includes the front contact of the armature 75 and the two coils of the relays 22A and 22 in series. In like manner on the third operation of the CT relay, the next two relays 33A and 33 are picked up and then they are retained energized as long as the relay 11 remains up. On the fourth operation of the CT relay, the relays 44A and 44 are picked up. Assuming relays HR, DR and ADR are all energized, then as the relay 44 picks up, the circuit to the approach energizing relay AP is opened at the back contact of the armature 65 and the relay CT remains up due to the fact that the relay 44 acts faster than the relay AP and the armature 65 of relay 44 is up to open the circuit of AP before the relay AP lifts its armature 54 sufficiently to open the circuit of the relay CT.

At the expiration of the release period of the relay 11A, its armature 72 drops to open the circuit to the relay 11. At the expiration of the release period of the relay 11, its armature 75 drops to cut off energy to the several groups of relays including the relay 44. As soon as this relay 44 becomes deenergized to again close the circuit for the relay

AP at its armature 65, the operation of reenergizing the chain of relays 11A to 44 is again repeated. By making the summation of the release time of the relays 11A, 11 and 44 equal to 0.5 second plus the normal period of a short impulse, it follows that the duration of the long impulse during which time current is supplied to the rails X and Y is equal to this total time, and which it will be recalled is somewhat greater than the time required for the deenergizing of the train carried relays 1, 1A and the remaining relays of any one of the several groups of train carried relays.

It follows then that when the relays HR, DR and ADR are all energized the track circuit current is given a code that consists of a group of four complete cycles of short impulses of 180 code frequency followed by a long impulse of 0.5 second duration and, that this group of impulses will be consecutively repeated. In the event the traffic conditions are such that the relay ADR is down—that is to say, the first two track sections in advance are unoccupied but the third track section in advance is occupied then the energizing of the group of relays of Fig. 2 will be stopped at the relay 33, and inasmuch as then the relay 33 is energized, the circuit to the relay AP is opened at the back contact of the armature 69. Under this condition, the code of the track circuit current will consist of a group of three complete cycles of short impulses followed by a long impulse of 0.5 second duration. Again if traffic conditions are such that the relay DR is down—that is to say, the first track section in advance is unoccupied but the second track section in advance occupied, then the operation of energizing the group of relays will be stopped at the relay 22, inasmuch as the circuit to the relay AP will now be opened at the back contact of the armature 67, and in this case the code of the track circuit current consists of a group of two cycles of short impulses followed by a long impulse. Again if the traffic conditions are such that the relay HR is down, then the relay AP remains deenergized and non-coded current is supplied to the rails X and Y.

Assuming that a train equipped with the apparatus of Fig. 1 enters the track section of Fig. 2 at a time when traffic conditions permit the relays HR, DR and ADR to be energized, that is, at least three track sections in advance are unoccupied, the alternating current supplied to the track rails X and Y under this condition will be a code that consists of a group of four impulses followed by a long impulse. From the foregoing description, it is recalled that a code of four short impulses and a long impulse will operate the group of relays that closes the circuit to the traffic governing relay A on the train and bring about the display of the cab sig-

nal 45 which we shall term a proceed signal.

Assume that the traffic conditions in advance of the section are such that the relay ADR is deenergized while relays HR and DR are energized, that is, the first two sections in advance are unoccupied and the third section in advance occupied, so that the code for the track circuit consists of a group of three short impulses and a long impulse. As was previously pointed out, this code operates the group of relays that results in the traffic governing relay R on the train being energized and the cab signal 46 displayed, which signal we shall term approach restricted. Again if the first section in advance is unoccupied and the second section in advance occupied so that the relay DR is down and relay HR up as the train enters the section of Fig. 2, the code supplied to the rails X and Y will consist of a group of two short impulses and a long impulse. Under these circumstances, the group of relays operated results in the train carried relay L being energized and the cab signal 47 displayed, which signal we shall term approach. Once again let us assume that as the train enters the track section of Fig. 2, the first section in advance is occupied and relay HR down. With relay HR deenergized, then the circuit for the relay AP is open and the current supplied to the rails X and Y is non-coded. With non-coded alternating current flowing in the rails, the armature 9 of the master relay MR is held steadily in the right-hand position. Under this condition, the train carried relays 1A and 1 were released at the expiration of their release period and the chain of relays on the train is deenergized, and in turn, the traffic governing relays L, R and A deenergized. This condition results in the cab signal 40 being displayed which we shall term a slow signal.

In the event a train already occupies the section of Fig. 2 as a second train enters the section, then the first train will shunt the track circuit current away from the following train. As the induced current in coils 14 and 15 dies away the armature 9 is moved to the left-hand and it then remains in this position as long as no current flows in the rails. As previously pointed out this condition results in the display of the slow cab signal 40.

To sum up the operation of the apparatus of Figs. 1 and 2, a proceed cab signal is displayed only in the event a definite code consisting of a group of four complete cycles of short impulses followed by a long impulse, is consecutively applied to the rails,—that an approach restricted indication is established on the train in the event that traffic conditions are such that a code consisting of a group of three short impulses and a long impulse is consecutively supplied to the rails. Again, an approach cab signal is displayed

in the event the code consists of two short impulses and a long impulse, and a slow cab signal is displayed whenever non-coded current is supplied to the rails or whenever the track circuit is shunted.

While the track apparatus as described in Fig. 2 will provide the proper codes required, it will be understood that my invention is not limited to this one form of code transmitting means and that other means for transmitting the above code may be equally as well employed such for example as the motor driven cam type of code transmitter.

In the form of the train carried equipment disclosed in Fig. 3, the master relay MR is provided with a second armature 77, the heel of which is connected to positive battery terminal B. The normal and reverse contacts of the armature 77 are connected to the outside terminals of the primary 78 of a decoding transformer DT which has a center tap that is connected to the negative terminal C. The secondary 79 of the decoding transformer DT is provided with a secondary circuit composed of reactor 80 and a condenser 81 in series. A full wave rectifier 82 is connected across a portion of the reactor 80 and the output terminals of the rectifier 82 are connected to the winding of the L relay. The parts of this secondary circuit are so proportioned that the relay L responds when the master relay MR is operated on 180 cycle current. The slow-release period of the relay L in this form of the train apparatus is of sufficient duration that its armature 83 is retained lifted during the long impulse, that is, it is greater than 0.5 second duration. It follows that whenever the master relay MR is operated on any of the codes cited previously in this description the relay L is retained energized, while whenever the relay MR is not operated on 180 cycle current the relay L is deenergized and its armature 83 drops.

The operation of energizing the chain of relays 1A to 4A inclusive of Fig. 3 is the same as that described in connection with the Fig. 1. However, the control of the traffic governing relays in the Fig. 3 is different from that described for the Fig. 1.

In Fig. 3 a code consisting of a group of three cycles of short impulses separated from the preceding and succeeding groups by a long impulse results in the relays 1A to 3 being energized during the three short impulses and then deenergized during the long impulse. With all the relays energized the front contacts of the respective armatures 24, 87 and 39 are closed and thus as the relay 1A becomes deenergized so that its armature 21 engages its back contact, current is momentarily supplied to the traffic governing relay A from the positive terminal B through the back contact of armature 21, the front contacts of the respective armatures 24, 87 and 39, the back

contact of armature 92 of the relay 4A, winding of relay A and to the negative terminal C. As stated in connection with Fig. 1, the relay A has a slow-release period greater than the time consumed by the group of short impulses plus the time of the long impulse and thus this relay A will remain energized as long as this code persists. With relay A energized, then the circuit to the proceed cab signal 45 is closed as follows: positive terminal B, front contact of armature 83 of the relay L, wire 88, front contact of the armature 89 of the relay A, wire 90, proceed cab signal 45 and to the negative terminal C.

With a code consisting of a group of two short impulses separated from the preceding and succeeding groups by a long impulse, the relays 1A to 2 of the Fig. 3 are energized during the two short impulses and then all deenergized during the long impulse. Under this condition, a circuit to the traffic governing relay R is completed during the interval that the relay 1A is down and the relays 1 and 2 are still up. This circuit for the relay R may be traced from the positive terminal B through the back contact of the armature 21, front contacts of the armatures 24 and 87 and the back contact of the armature 39. As stated in connection with Fig. 1, the relay R has a slow-release period greater than the time consumed by the short impulses, plus that consumed by the long impulses and thus the relay R is retained energized as long as this code persists. With relay R energized then the circuit is closed to the approaching restricted cab signal 46 as follows: positive terminal B, front contact of armature 83, wire 88, back contact of armature 89, front contact of armature 91, cab signal 46 and to negative terminal C. In the event the 180 impulses are not arranged in groups which are separated by a long impulse, the relay L of Fig. 3 will remain energized but the relays R and A are both deenergized due to the fact that the relay 4A is retained energized after the fourth impulse. With all the relays 1A to 4A inclusive energized, then the circuit to relay A is open at the back contact of armature 21 and the back contact of armature 92 and the circuit to the relay R is held open at the back contact of armature 21 and at the back contact of armature 39. Under this condition where relay L is energized and both relays A and R deenergized, a circuit is closed to the approach signal light 47 which circuit includes the front contact of the armature 83 and the back contacts of the armatures 89 and 91 as will be readily understood in the Fig. 3. In the event the master relay MR is not operated on code and the relay L is down, then the circuit to the slow cab signal 40 is complete as will be evident by an inspection of the Fig. 3.

To sum up the operation of the apparatus of Fig. 3, the proceed cab signal 45 is dis-

played when the code of the track circuit consists of a group of three short impulses separated from the preceding and succeeding groups by a long impulse. The approach 5 restricted cab signal 46 is displayed when the code consists of two cycles of short impulses and a long impulse. The approach cab signal 47 is displayed when the code consists of short impulses only, and the slow cab signal 40 is 10 displayed when non-coded current flows in the track circuit or when the track circuit is shunted.

The track apparatus to coordinate with the train carried apparatus of Fig. 3 would 15 deviate from that shown in the Fig. 2 only in the manner of controlling the approach energizing relay AP through the control relays HR, DR and ADR. To provide for a code consisting of three short impulses between successive long impulses in response to a 20 proceed traffic condition would require that the circuit for the relay AP that includes the front contacts of armatures 61, 62 and 63 be connected to the negative terminal through 25 the back contact of the armature 69 of the relay 33. For the apparatus of the Fig. 2 to supply a code consisting of two short impulses between successive long impulses in response to an approach restricted traffic condition, it requires that the circuit for the 30 relay AP that includes the front contacts of the armatures 61 and 62 and the back contact of the armature 63 be connected to the negative terminal through the back contact of the armature 67. Again in Fig. 2 for the apparatus to supply a code consisting of short impulses only, under caution conditions, it requires that the circuit for the relay AP that 35 includes the front contact of armature 61 and the back contact of armature 62 be connected directly to the negative terminal C.

Again referring to the Fig. 3, if a second secondary circuit for the decoding transformer DT be provided and this second secondary circuit be tuned to a code frequency other than the 180 cycles per minute, say to a frequency of 120 cycles per minute, it is apparent that this second secondary circuit could control a relay similar to the relay L 45 and this additional relay could then be used to control additional signals if such were required.

It is apparent from the foregoing description that the apparatus of my invention provides a system that is practically immune from false proceed indications due to shock excitation when operating on electric roads or when operating over alternating track circuits, and that a large number of distinctive 50 indications can readily be provided without a great outlay of apparatus.

Although I have herein shown and described only certain forms of apparatus embodying my invention, it is understood that various changes and modifications may be

made therein within the scope of the appended claims without departing from the spirit and scope of my invention.

Having thus described my invention, what I claim is:

1. In combination, a signaling circuit, a plurality of inter-inclusive groups of sending relays associated with said signaling circuit for supplying said circuit with a plurality of different codes of current impulses by operating the relays of the selected group in a cyclic order, a plurality of inter-inclusive groups of receiving relays also associated with said circuit adapted to be selectively operated in a cyclic order by the different codes of current impulses, and a plurality of signals selectively controlled by the said groups of receiving relays. 70 75

2. In combination, a signaling circuit, a plurality of inter-inclusive groups of sending relays associated with said signaling circuit, means for operating the relays of a group in a cyclic order to supply the signaling circuit with a respective code of current impulses, a plurality of inter-inclusive groups of receiving relays also associated with said signaling circuit, means for operating in a cyclic order the relays of a group of receiving relays in response to the code supplied by a respective group of sending relays to the signaling circuit, and a plurality of signals selectively controlled by the said groups of receiving relays. 80 85 90

3. In combination, a signaling circuit, a plurality of inter-inclusive groups of sending relays associated with said signaling circuit, means for operating the relays of a group in a cyclic order to supply the signaling circuit with a respective code of current impulses, a plurality of inter-inclusive groups of receiving relays also associated with said signaling circuit, means for operating in a cyclic order the relays of a group of receiving relays in response to the code supplied by a respective group of sending relays to the signaling circuit, and a plurality of signals selectively controlled by the said groups of receiving relays. 100 105

4. In combination, a signaling circuit, a code transmitting means adapted to supply to said signaling circuit code impulses of alternating current each of which has a predetermined period of duration, a slow-release device having a release period greater than the said predetermined period, and an automatic means to periodically render said slow-release device effective to retain said code transmitting means in its current supplying condition during its release period to supply said signaling circuit with a code having a group of current impulses separated from the preceding and succeeding groups by a relatively longer impulse of current. 110 120 125

5. In combination, a signaling circuit, a code transmitting means adapted to supply 130

to said signaling circuit code impulses of alternating current each of which has a predetermined period of duration, a slow-release device having a release period greater than 5 the said predetermined period, an automatic means to periodically render said slow-release device effective to retain said code transmitting means in its current supplying condition during its release period to supply 10 said signaling circuit with a code having a group of alternating current impulses separated from the preceding and succeeding groups by a relatively longer impulse of alternating current, and means controlled from 15 a distant point to select the number of impulses in a group.

6. In combination, a signaling circuit, a code transmitting means adapted to supply to said signaling circuit code impulses of 20 alternating current each of which has a predetermined period of duration, a plurality of groups of relays each group of which has a release period greater than the said predetermined period, a circuit including an armature operated by the code transmitting means to energize in cascade the relays of each of 25 said groups, means rendered effective by the energizing of the last relay of a group to deenergize the relays of the group and to retain the code transmitting means in its current supplying condition during the release period of 30 said relays to supply said signaling circuit with a code having a group of alternating current impulses separated from 35 the preceding and succeeding groups by a relatively longer impulse of alternating current, and means controlled from a distant point to select the groups of relays.

7. In combination, a conductor, a code 40 transmitting device, a circuit including a source of alternating current and an armature operated by said code transmitting device to supply code impulses of current to the conductor, a plurality of inter-inclusive 45 groups of relays, a circuit including an armature operated by said code transmitting device to energize in cascade the relays of each of said groups, means rendered active upon the energizing of the last relay of a group to deenergize the relays of the group after a 50 predetermined interval, and means controlled by said groups of relays to control the operation of said code transmitter.

8. In combination, a track section, a code 55 transmitting device, a circuit including a source of alternating current and an armature operated by said code transmitting device to supply code impulses of current to the rails of the section, a pair of slow-releasing 60 relays, a plurality of inter-inclusive groups of relays each including the said slow-releasing relays, a circuit including an armature operated by the code transmitting device to energize in cascade the relays of each group, means rendered active upon the

energizing of the last relay of a group to de-energize concurrently at the expiration of the release period of said slow-releasing relays the remaining relays of the group, and means controlled jointly by traffic conditions and the groups of relays to control the operation of the code transmitting device. 70

9. A train control system, including a plurality of train carried quick acting relays capable of being arranged into different groups, a pair of slow release relays on the train, a code following relay adapted to energize the said pair of relays and a group of said quick acting relays successively in response to a code consisting of a group of current impulses of substantially equal duration and to deenergize the said pair of slow releasing relays successively and the group of relays concurrently in response to a current impulse of relatively longer duration, a track-way traffic controlled means to select the number of current impulses that go to make up a code group in accordance with different traffic conditions and to separate a code group of impulses from the preceding and succeeding groups by a current impulse of relatively longer duration, and a plurality of train carried signaling circuits selectively controlled by said groups of relays. 80

10. A train control system, including a track section, a vehicle to travel over said track section, a trackway armature, means to periodically operate the armature at a given rate, a circuit means governed by said armature to supply code impulses of current to said track section in step with its operation, a plurality of different groups of trackway relays with the relays of each group adapted to be energized successively as said armature is operated and to hold said armature stationary when all of the relays of the group are energized, means to deenergize the relays of a group concurrently at the end of a predetermined stationary period and thereby again permit the operation of the armature, means to select the group of relays in accordance to traffic conditions, a code following relay on the vehicle responsive to the current impulses supplied to the track section, and a plurality of signaling circuits on the vehicle selectively controlled by the code following relay. 95

11. A train control system, including a track section, a vehicle to travel over the section, a trackway armature, means to periodically operate the armature at a given rate, a circuit means governed by said armature to supply code impulses of current to said track section in step with its operation, a plurality of different groups of trackway relays with the relays of each group adapted to be energized successively as said armature is operated and to hold said armature stationary when all of the relays of the group are energized, means to deenergize the relays of a 105

group at the end of a predetermined stationary period and thereby again permit the operation of the armature, means to select the group of relays in accordance with traffic 5 conditions and thereby establish different codes of current impulses, a code following relay on the vehicle, a plurality of relays on the vehicle adapted to be energized successively in response to the operating of the code 10 following relay by the current impulses supplied to the track section and to be deenergized during the stationary period of track-way armature, and a plurality of signaling devices on the vehicle selectively controlled 15 in response to the energizing and deenergizing of the vehicle relays.

In testimony whereof I affix my signature.
GEORGE W. BAUGHMAN.
